(57) **CLAIM**

The ornamental design for: toilet seat having lift grip molded therein, as shown and described.

DESCRIPTION

FIG. 1 is a front elevational view showing my new design for a toilet seat having lift grip molded therein;
FIG. 2 is a top elevational view thereof;
FIG. 3 is a right side elevational view thereof, the left side being a mirror image thereof;
FIG. 4 is a rear elevational view thereof; and,
FIG. 5 is a bottom elevational view thereof.
